UNITED STATES PATENT OFFICE

CARL R. HENNICKE, OF CLEVELAND, OHIO, ASSIGNOR TO THE EBERHARD MANUFACTURING COMPANY, OF CLEVELAND, OHIO, A CORPORATION OF OHIO

DOOR LATCH

Application filed November 25, 1927. Serial No. 235,451.

This invention relates to closure fasteners, and more particularly to a latch intended for use primarily on commercial bodies of motor vehicles where sliding doors are used in the driver's compartment, but it is also applicable for use with other types of doors.

According to this invention there is provided a latch of very simple and compact construction which can be cheaply manufactured and which can be used on a very narrow door stile. The latch can be used on both right and left-handed doors without any change, and can be used for latching the door open as well as closed. The latch is provided with an inside handle and provision is made also for the use of an outside handle, the construction being such that the outside handle is brought close to the edge of the door. The compact construction of the latch and the convenient disposition thereof on the door permits the door to be opened a maximum amount.

The invention may be readily understood by reference to the accompanying drawings, in which—

Figure 1 is a side elevation showing a portion of a sliding door and its frame with a latch embodying my invention applied thereto;

Figure 2 is a side elevation of the latch applied to the door, part of the door being broken away to show the construction of the outside handle;

Figure 3 is a plan view of the casing or housing of the latch;

Figure 4 is a section on the line IV—IV of Figure 3;

Figure 5 is an elevation of the cover plate for the casing;

Figure 6 is a vertical section on the line VI—VI of Figure 5;

Figure 7 is an elevation of the bolt or sliding plate inside the casing;

Figure 8 is a side elevation of the member shown in Figure 7;

Figure 9 is a side elevation of the combined rollback and handle construction;

Figure 10 is a front elevation of the member shown in Figure 9; and

Figure 11 is a perspective view of one of

the catches or keepers for cooperation with the latch.

In the drawings, A designates a sliding door having a stile a. B designates the door frame at one side of the sliding door and C designates the frame at the other side of the door, the door being adapted to slide toward the post B enclosing the doorway and to slide back of the post C in opening the door. As shown in Figure 1, the door is partially open.

The latch, which is adapted to be secured to the stile A, comprises a casing 2 having side flanges 3 and end flanges 4. On each of the end flanges 4 is a pad 5. In each of the side flanges 3 is an opening 6 and extending inwardly from the side flanges 3 below the opening 6 are lugs 7. The casing is preferably made of pressed sheet metal and the lugs 7 are struck inwardly from the flanges 3 to form the opening 6. In the face of the casing is a circular opening 8 and in the top end of the flange 4 is a slot 9. Received in the casing is a sliding plate or bolt 10 which is also preferably formed of sheet metal. The central portion of the member 10 is of substantially the same width as the inside of the casing 2, and has a pair of outwardly turned lugs 11 thereon, one of these lugs being at each side of the plate, as best shown in Figures 7 and 8. The upper end of the sliding plate 10 is bifurcated to provide a central opening 12 with lugs 13 at each side thereof. Each of the lugs 13 has an overturned lug 14 thereon. The portion of the plate below the lugs 11 is of reduced width, this portion of reduced width being designated 15. At each side of the portion 15 is an outwardly turned flange 16. Each of the flanges 16 has a laterally turned lug 17 at the lower end thereof, the lugs 17 being turned in opposite directions away from each other.

The narrow portion 15 of the sliding plate extends between the lugs 7 in the casing. The height of the lugs or flanges 16 is preferably substantially equal to the depth of the casing so that when the sliding plate is in the casing with the flanges 11 and 16 turned toward the plate part thereof the outer surface of the plate 10 will be substantially flush with the edges of the flanges 3 and 4. A cover plate 18 is placed over the casing 2 but includes

the sliding plate 10. The cover plate 18 may be riveted or otherwise fitted to the casing by means of rivets 19 passing through registering holes 20 and 21 in the cover plate and casing respectively. The casing and cover plate 18 also have registering holes 22 through which bolts or screws 23 pass to secure the lock to the door. The cover plate 18 has a circular hole 24 which registers with the opening 8 in the casing. The cover plate also has inwardly struck projections 25 thereon.

In the casing, between the casing and the cover plate, is a rollback having a central portion 26 with lateral projections 27 at each side thereof. The projections 27 engage under the lugs 14 of the sliding plate or bolt. The ends of the part 26 are round and are reduced as indicated at 28. These portions 28 are received in the openings 8 and 24 of the casing and cover plate respectively to provide a rotatable mounting for the rollback. Projecting upwardly from the portion 26 through the slot 9 is a handle 29. The part 26 of the rollback has a square hole 30 there-through.

Inside the casing, between the inwardly turned lugs or ears 7 of the side flanges 3 and the end lugs 17 of the sliding plate or bolt 10, are compression springs 31 which function to urge the plate 10 downwardly. The flanges 16 serve to confine the springs, and the projections 25 also function to hold the springs in proper position in the casing.

In the normal position of the various parts, the end lugs 17 are spaced above the bottom flange 4 of the casing and the springs 31 urge the lugs 14 of the bolt into contact with lugs 27 of the handle. The lugs or ears 11 project down part way but not entirely across the openings 6 in the side flanges 3, and the handle 29 is vertical with the tops of the lugs 27 horizontal. The lugs 14 are in contact with the tops of the lugs 27 of the tumbler.

For cooperation with the lugs 11 there is provided one or more keeper elements having a base portion 32 with an outwardly extending shank portion 33 on which is a head 34. One of these keeper members is mounted on the post B and another is mounted on the frame C.

When the door is closed, the keeper head 34 enters the opening 6 at one side of the casing lifting the bolt 10 against the action of the springs 31. The springs then snap the bolt back so that the lugs 11 engage in back of the head 34. To open the door the handle 29 is rocked in either direction. One of the lugs 27 engaging under a lug 14 of the plate 10 slides the plate 10 upwardly until the lug 11 is raised out of cooperating position with the keeper head 34. By reason of the fact that there are two lugs 11 and an opening 6 at the edge of the casing, the latch can be used on either a right or left handed door. It can also be used to cooperate with the keeper ele-

ment on the post C for holding the door open. This is desirable on cabs of trucks for summer driving.

For opening the door from the outside there is provided a square stem 35 that passes through the door and through the square hole 30 in the portion 26 of the rollback. On the outer end of the stem is a handle or wings 36 for turning the stem 35 to operate the rollback. The handle 36 is preferably set in a cup 37 in a recess in the door, as best shown in Figure 2.

The latch as described is of extremely simple construction and can be cheaply manufactured. It has few operating parts and its operation is positive. The parts can be assembled into a compact casing so that the latch does not take up much room on the door. Consequently, it permits the door to be opened a maximum distance. The parts can be cheaply manufactured.

The lugs 11 may be provided with stiffening ribs 11a, these ribs being pressed into the metal and being continued into the body of the plate 10, as shown in Figures 7 and 8.

While it is preferred that most of the parts be made from pressed sheet metal, it will be understood that they can be otherwise constructed and that various changes and modifications can be made in the construction and arrangement of parts within the contemplation of my invention and under the scope of the following claims.

I claim:

1. A latch comprising a casing, a cover plate for the casing, and a bolt member in the casing comprising a plate having two lugs thereon intermediate the ends thereof, having two lugs at the top thereof and having a lug at the bottom thereof, an internal lug in the casing, a spring interposed between said internal lug and the bottom of said bolt member, a rollback rotatably supported in the casing at the top thereof having laterally projecting lugs for cooperation with the lugs on top of said bolt member, said casing having openings therein at each side thereof, the lugs on said bolt member intermediate the ends thereof normally projecting part way across the said openings in the casing.

2. A latch comprising a casing, a bolt member in the casing comprising a plate having intermediate lugs thereon and having lugs at each end thereof, the intermediate lugs being of a height substantially equal to the depth of the casing, a cover plate for the casing against which said bolt member is adapted to bear, springs in the casing acting against the lugs at the bottom of the bolt member and a rollback in the casing adapted to cooperate with the lugs on the top of said bolt member, said rollback having a handle thereon projecting through the casing.

3. A latch comprising a casing having side

and end walls, a cover plate on the casing, a rollback rotatably supported in the casing and cover plate, a bolt member in the casing having a lug at one end thereof for cooperation with the rollback, said bolt member having a lug at the opposite end thereof, a lug in the casing, a spring interposed between the casing lug and the lug at the bottom of said bolt member, one of the sides of the casing having an opening therein, and means on the bolt member adapted to normally project part way across said opening.

4. A latch comprising a casing having side and end flanges, a bolt member in the casing having a wide intermediate portion with a lug at each side thereof, said bolt member having a bifurcated upper portion with a leg at each side of the bifurcation, each leg having a lug thereon, a reduced extension at the opposite end of the bolt member having a flange at each side thereof, each flange having a laterally turned lug at the bottom thereof, each of the side flanges of the casing having an opening therein, said casing having a lug at each side thereof below said openings, the reduced portion of the bolt extending between said lugs in the casing, and a pair of springs in the casing between the lugs in the casing and the said lugs at the bottom of the flanges of the bolt member, a rollback rotatably supported in the casing having a pair of lugs thereon for cooperation with the lugs on the legs of the upper end of the bolt member, a handle on said rollback projecting through the casing, and a cover plate for the casing.

In testimony whereof I have hereunto set my hand.

CARL R. HENNICKE.
